MANIFOLDING DEVICE

Mark W. Shoemaker, Chicago, Ill., assignor to The
Rotary Printing Company, Norwalk, Ohio, a
corporation of Ohio

Application March 30, 1937, Serial No. 133,858

9 Claims. (Cl. 197—133)

The present invention relates to an improved apparatus for aligning continuous forms on a flat bed typewriting machine, and has for one of its objects the provision of a simple and efficient attachment which will operate to maintain a plurality of continuous forms in accurate registration during use. Forms of this character comprise a plurality of super-imposed strips and are usually removed from a flat pack or roll that is suitably supported at the rear of the machine. These super-imposed strips sometimes become misaligned as they are pulled from the pack or roll through the machine onto the flat bed of the typewriting mechanism. True registration is necessary, however, in order to maintain accurate alignment or similarity between the typed portions on the various forms, or between the typed portions and previously printed portions on the various forms.

Referring now to the drawing, Fig. 1 is a perspective view of a flat bed typewriting machine, equipped with my invention; Fig. 2 is a top plan view of the machine, with the typewriter removed, and illustrating the super-imposed webs in position and Fig. 3 is a vertical section taken along the lines 3—3 of Fig. 2.

The machine with which I have shown my invention has a standard 10 that supports a trackway or frame 11, providing a platen 14, across which a typewriter 12 is adapted to be shifted in the usual manner. The forms may be stored in any desired manner, such as for instance, in a flat pack or a continuous roll, not shown, but in either instance, they may be on the floor or by the standard 10. As the forms are withdrawn from the roll or pack, they extend upwardly and then forwardly around suitable guide bars across the platen 14 beneath the typewriter 12.

With the machine illustrated, transfer or carbon strips are interleaved between the record strips or forms adjacent the regions of typing, and are usually carried on a roll 23 that is journaled at the side of the machine. The transfer strips move transversely of the direction of movement of the record strips and therefore may be used as long as they produce legible copies.

As illustrated, the web or record strips 15 extend upwardly from a suitable support, not shown, around a guide bar 16, and thence forwardly in a substantially horizontal plane, beneath a pair of guide bars 17, over guide bars 18 and 19, under a guide bar 20, over a guide bar 21, and thence across the platen 14 of the typewriter mechanism 12. At the forward end

of the bed are a series of aligning pins 24, which are arranged to engage perforations 25 formed in the web. The perforations of the web are normally maintained in engagement with the pins 24 by a spring-pressed clamp 27, carried by a lever 28 pivoted, as at 29, to the frame of the machine.

The paper is maintained taut across the bed 14 by a weighted roller 30 carried by a pair of arms 31, pivoted to the guide bar 20, adjacent its ends. The guide bar 20 is preferably mounted on brackets 33, which may be secured to the machine by bolts 34. This weighted roller, together with the routing of the paper due to its passage between the guide bars 16, 17, 18, 19, 20 and 21 serves to tension the paper across the bed. Stop pins, one of which is indicated at 33 in Fig. 2, are removably positioned in suitable openings 36 in the plate 33, preventing excessive downward movement of the arm 31, which carries the weighted roller 30. The perforations 25, which cooperate with the pins 24, and other aligning pins hereinafter to be described, are provided in each form adjacent one end thereof and above respective scoring lines 26. The perforations in each form are in exactly the same location with reference to the edges thereof, as in all other forms. Hence, it will be seen that the pins 24 will serve to retain the forward edge of the forms in alignment.

It has been found, however, that to insure accurate alignment of the super-imposed strips, the paper must be aligned when it is being pulled across the bed to position a fresh sheet or page beneath the typewriter 12. For this purpose, I have provided a second set of pins 40, arranged to engage a subsequent set of openings 25 in the strips or forms, as the latter are being drawn forwardly across the table.

When the operator desires to bring a fresh sheet beneath the typewriter, he depresses a foot pedal 50, which, through the medium of a link 51 interposed between the pedal and the lever 28, raises the clamp 27 out of engagement with the forward edge of the forms. The operator then raises the forms out of contact with the pins 24 and draws them forwardly. Simultaneously with the raising of the clamp 27, the pins 40 are brought into position to engage a set of openings 25, as the forms are drawn forwardly. This is accomplished as shown in Figs. 1 and 3, by a link or rod 52, which is interconnected between the pedal 50 and an arm 53, that is secured to a ball 54, which is pivoted as at 55 to

the plate 33, heretofore described, and which carries the pins 40 as indicated in Fig. 3.

Consequent upon the depression of the pedal 50 the pins 40 are moved from the full-line position, shown in Fig. 3, to the dotted-line position therein shown, and are maintained in the latter position as long as the pedal is depressed. As the operator draws the paper forwardly, the openings 25 which lie immediately to the rear of the pins, that is to the left in Fig. 3, are drawn 10 into registration with such pins, whereupon the pins 40 enter the openings and prevent further forward movement of the forms at that point. As the operator continues to draw the paper forwardly, the loop 56 formed in the paper, due to 15 the weighted arm 38, is substantially eliminated, raising the weight to the dotted line position 38a, shown in Fig. 3, whereupon the forward openings 25 of the forward sheet may be brought into registration with the pins 24.

20 It will be noted that when the openings in the forward sheets or forms are placed on the pins 24, the sheet is tensioned between the pins 24 and the pins 40 by the weighted roller 38, thereby bringing all of the super-imposed sheets into 25 registration and insuring accurate alignment of the impressions later to be made on the sheet. The operator then releases the pedal 50, and consequent upon its release, a spring 58 draws the clamp 27 into engagement with the sheets. The 30 release of the pedal likewise releases the tension on the link or rod 62, whereupon the pins 40 are withdrawn from engagement with the forms, and the weighted roller 38 draws forwardly that portion of the forms lying to the rear of the roller, 35 again forming a loop 56 in the web. The arrangement is such that the reforming of the loop 56, due to the action of the weight 38, draws the openings 25a, from which the pins 40 are withdrawn, into a position where they will not be 40 re-engaged by the pins 40 consequent upon the next subsequent depression of the pedal 50 which returns the pins to the dotted-line position shown in Fig. 3, as heretofore described.

The present invention is advantageous in that 45 it may be readily attached to an existing machine, in an extremely simple operation, and yet is capable of being used for maintaining very accurate registration in the forms, without departing materially from the usual movements 50 that are necessary to withdraw and cut off the forms.

I claim:

1. In a device for registering continuous super-imposed forms in a typewriter machine, the combination of stationary means for engaging and aligning a set of openings in each of the respective superimposed forms, releasable means adapted to be projected into the path of the forms, for engaging and aligning another set of openings in the respective forms, and means disposed between said means for tensioning the respective forms while they are held in engagement and alignment by the stationary means and the releasable means, said last-named means acting 55 automatically consequent upon the release of said releasable means to progress a portion of the forms which were acted upon by the releasable means.

2. In a machine for registering continuous super-imposed forms in a typewriter machine, the combination of means for engaging and aligning a set of openings in each of the respective forms, releasable means for engaging and aligning a second set of openings in the respective forms adapt-

ed to be projected into the path of the forms, and means for tensioning the forms while they are held in alignment and adjustment by the aforesaid means, said last-named means being arranged and adapted to act automatically consequent upon the release of said releasable means to progress a portion of the forms which were acted upon by said releasable means. 5

3. A device for registering superimposed continuous forms in a typewriter machine, wherein the forms each have a plurality of openings spaced longitudinally thereof, comprising stationary means for engaging and aligning a set of openings in the respective forms and releasable gripping means coacting with said means to grip 10 the forward edge of the forms, a second releasable means adapted and arranged to be projected into the path of the forms to engage and align another set of openings in the respective forms, releasable means to simultaneously release 15 said gripping means and project the second-named releasable means into the path of said openings, whereby such openings will be engaged by the second-named releasable means consequent upon the progressing of the forms by the 20 operator, and tensioning means acting on the forms while they are held in engagement and alignment by said stationary means, and said second releasable means.

4. A device for registering superimposed continuous forms in a typewriter machine, wherein each of the forms has a plurality of sets of spaced openings, comprising a set of stationary pins adapted to engage the foremost set of openings in the respective forms, releasable gripping means to normally maintain such openings in the forms in engagement with said pins, a set of pivotally mounted pins adapted to be swung about their pivots to project them into the path of a second set of openings in the respective forms, whereby such succeeding openings will be engaged by said pivotally mounted pins consequent upon the progressing of the forms by the operator to thereby align and arrest the progress of the forms, means normally acting to tension the respective forms while they are held in engagement and alignment by the two sets of pins, said tensioning means being arranged and adapted to automatically progress a portion of the forms engaged by the pivotally mounted pins, consequent upon the release of said gripping means, whereby subsequent operation of said pivotally mounted pins will position them for engagement with the next succeeding openings in the forms. 45

5. In a machine of the character described, the combination of a typewriter bed, a pair of 55 stationary prongs at the forward edge of said bed projecting upwardly therefrom to engage and align the respective openings in continuous superimposed forms, a second set of movably mounted prongs adapted to engage another set of 60 openings in the respective forms, and means disposed intermediate said pairs of prongs to tension the forms while they are held in engagement by the stationary pair of prongs and the movably mounted prongs.

6. In a machine of the character described, the combination of a frame, stationary means rigidly secured to said frame for engaging and aligning a set of openings in respective superimposed form, a second means movably supported by said 70 frame for engaging and aligning a second set of openings in the respective forms, tensioning means comprising a roller and a pair of pivotally mounted arms connecting the roller to the frame, said roller engaging the forms while they are 75

held in alignment by the stationary engaging means and the movable engaging means.

7. In a machine of the character described, the combination of a typewriter bed, a pair of stationary prongs at the forward edge of said bed projecting upwardly therefrom to engage and align the respective openings in several superimposed continuous forms, a second set of movably mounted prongs adapted to engage and align another set of openings in the respective forms, said last-named prongs when in engagement with the openings in the forms being in substantially the same horizontal plane as the first named prongs, and tensioning means disposed intermediate said pairs of prongs to act upon the forms while they are held in engagement and alignment by said pairs of prongs, and to form a downwardly extending loop in said forms when the movably mounted prongs are withdrawn from the openings in respective forms.

8. A device for registering super-imposed continuous forms, comprising a table across which the forms are to be passed, a pair of aligning pins at the forward end of the table for engagement with aligning holes provided at form length intervals in the forms, a pair of bars extending rearwardly from the table, a pair of guides carried by said bars and beneath which the forms pass in their advance toward the table, a second pair of spaced guides disposed between the first-named guides and above which the forms pass in their advance toward the table, a pair of arms pivoted at one end to said bars, and carrying at their other end a plurality of pins adapted and arranged to be moved into the path of the openings in the forms and between the guides of the second-named pair, a pair of links, one end of each link being pivoted to said bars, a weight carried by said links adjacent their other ends and resting on the forms between the pivoted pins and the platen to tension the forms, an adjustable stop to restrict the downward movement of the weight in various positions, a foot operable pedal, and a connection between the pedal and the pin carrying arms whereby the pins may be rocked about the pivots of such arms as desired, and where said weight acts to advance that portion of the forms adjacent said pivoted pins consequent upon the disengagement of such pins from the forms.

links and resting on the forms between the pivoted pins and the table, an adjustable stop carried by the table to restrict the downward movement of roller in various positions, a foot operable pedal and a connection between the pedal and the pin carrying arms, whereby the pins may be rocked about the pivots of such arms as desired.

9. A typewriter feeding mechanism for aligning a plurality of superimposed continuous forms over a platen across which the forms are advanced to bring a fresh form into writing position on the platen, comprising a pair of aligning pins at the delivery side of the platen for engagement with aligning holes provided at form length intervals in the forms, a pair of bars extending rearwardly at the intake side of the platen, a pair of spaced guides carried by said bars and beneath which the forms pass in their advance toward the platen, a second pair of spaced guides disposed between the first-named guides and below the forms, a pair of arms pivoted at one end to said bars and carrying at their other end a plurality of pins adapted and arranged to be moved into the path of the openings in the forms and between the guides of the second-named pair, a pair of links, one end of each link being pivoted to said bars, a weight carried by said links adjacent their other ends and resting on the forms between the pivoted pins and the platen to tension the forms, an adjustable stop to restrict the downward movement of the weight in various positions, a foot operable pedal, and a connection between the pedal and the pin carrying arms whereby the pins may be rocked about the pivots of such arms as desired, and where said weight acts to advance that portion of the forms adjacent said pivoted pins consequent upon the disengagement of such pins from the forms.

MARK W. SHOEMAKER.
